JACOB JACOBSEN, OF SAN FRANCISCO, CALIFORNIA, ASSIGNOR OF ONE-THIRD TO WILLIAM SAMUELS AND ONE-THIRD TO BRUNO W. HENNING, BOTH OF SAN FRANCISCO, CALIFORNIA.

ROTARY PUMP.

1,270,522.

Specification of Letters Patent. Patented June 25, 1918.

Application filed April 7, 1917. Serial No. 160,395.

To all whom it may concern:

Be it known that I, JACOB JACOBSEN, a citizen of the United States, residing in the city and county of San Francisco and State 5 of California, have invented new and useful Improvements in Rotary Pumps, of which the following is a specification.

This invention relates to a rotary pump.

One of the objects of the present invention is to provide a simple, compact, substantial, cheaply manufactured rotary pump comprising a cylindrical casing, a piston turnably mounted and eccentrically positioned within the casing, a head member on each end of the casing, in one of which is journaled a driving shaft supporting the piston while the other carries a stationary shaft centrally positioned with relation to the cylindrical casing, and a plurality of radially positioned vanes turnably mounted on the stationary shaft and extending through slots formed in the piston. The invention also comprises a novel ball bearing support for the driving shaft and piston and turnably mounted guiding members for the vanes. Further objects will herein-after appear.

Having reference to the accompanying drawings:—

Figure 1 is a central, vertical, cross section through the pump.

Fig. 2 is a section on line 2—2 of Fig. 1.

Fig. 3 is a perspective view of one of the vane guides.

Fig. 4 is a perspective view of one of the vanes.

Referring to the drawings in detail, A indicates a cylindrical-shaped casing, interiorly of which is mounted a piston 2. Formed integral with one end of the casing or otherwise secured thereto is a head member 3, in which is journaled a driving shaft 4 supporting the piston. Secured to the opposite end of the casing is a removable head member 5 and extending through said head member and rigidly secured therein is a stationary shaft 6, which is centrally positioned with relation to the cylindrical casing. The shaft 4 and the piston supported thereby are eccentrically positioned with relation to the casing, thereby forming a fluid passage 7 in the upper portion of the casing which communicates with an intake passage 8 and a discharge passage 9.

The piston proper is cored out or hollow, as shown at 10, and is furthermore radially

slotted and provided with recesses 11 for the reception of the vane guides 12. These vane guides are in reality pins of suitable diameter which are longitudinally slotted, 60 as at 13, to permit the vanes to pass therethrough, and the pins are sufficiently long to form perfect bearings and guides from end to end of each individual vane. The vanes consist of rectangular shaped plates 65 14, extending through the slotted portions of the guides 12 and each vane is provided with an inwardly extending arm 15 and a bearing ring 16 which embraces the stationary shaft 6. The position of the arms and 70 the bearing rings 16 varies, as shown in Fig. 2. That is, two vanes will have the arms formed on the ends of the blades on opposite sides, as shown at 17 and 18 while the other two vanes will have their arm extensions 75 approximately centrally positioned, as shown in Fig. 4.

In actual operation when assembling the pump as here shown, it is first necessary to insert the shaft 4 and the piston in the direction of arrow a. The vane guides or slotted pins 12 are then placed in the piston pockets and the vanes inserted through the slotted portions 13. An exterior ring 19 is then applied to the face of the piston and 80 secured thereto by screws 20 or any other suitable means. The head member 5, supporting the stationary shaft 6 and an annular ball race 21, is then placed in position, care being taken that the stationary shaft 90 passes through the several bearing rings 16. The head is then secured by screws 22 and the pump as a whole is assembled.

Power transmitted to shaft 4 when the pump is thus assembled will cause the piston to revolve therewith and the vanes 4 to turn about the stationary shaft 6. The eccentric position of the piston with relation to the bearing support of the vanes will in this manner cause each vane to become retracted and extended with relation to the piston once during each revolution; the extended position of the blades taking place gradually during their passage through the upper chamber 7. Water or other fluid 100 handled by the pump is in this manner taken from the intake and discharged through the outlet 9, and practically any pressure desired may be obtained as leakage losses will be comparatively small. This can readily 110 be seen if the pump is handling water, oil, or like material, by referring to Fig. 1, as

each vane during its retraction forms a pocket 30 in the face of the piston which carries over a sufficient quantity of the water or oil to form a packing between the lower 5 face of the piston and the cylinder. This is an important advantage.

This manner of automatically lubricating or packing the piston is found to be highly efficient as it not only reduces friction but 10 also eliminates wear to a great extent. This is also true of the vanes. Friction losses therethrough are in this instance practically reduced to a minimum as they are positively held against contact with the inner surface 15 of the cylindrical casing by means of the stationary shaft. That is, clearance of a thousandth of an inch may be successfully maintained between the outer ends of the blades and the inner surface of the casing, thereby 20 entirely relieving friction which has heretofore been extremely objectionable in pumps of this type. Friction is also reduced in the main shaft bearing by providing the annular ball races shown at 21 and 41, and lubrication of the bearing rings is also taken care 25 of by the lubricating cup 42 which delivers oil through the stationary hollow shaft to the individual bearings. Friction and leakage losses are in this manner taken care of 30 throughout the pump and a high efficiency and comparatively long life are maintained without constant repairs and adjustment.

The materials and finish of the several parts of the pump are such as the experience 35 and judgment of the manufacturer may dictate.

I wish it understood that various changes in form, proportions and details of construction may be resorted to within the scope of 40 the appended claims and that I do not wish to limit myself to the specific design and construction here shown.

Having thus described my invention, what I claim and desire to secure by Letters 45 Patent is—

1. A rotary pump comprising a cylindrical casing, a rotary piston eccentrically disposed therein and radially slotted, one end of each slot being opened, a bearing pin 50 rotatably seated in each slot and provided with a slot also opening through the end of said pin in registry with the piston slot, vanes insertible through the open ends of the respective pin and piston slots and slidably supported by said pins for radial movement, and concentrically arranged means connecting the vanes.

2. A rotary pump comprising a cylindrical casing, a piston eccentrically positioned 60 within the casing and driven from a shaft extending through one side of the casing, a stationary shaft secured in the opposite end of the casing and centrally positioned there-

in, said shaft extending through one end of the piston, a plurality of vanes turnably 65 mounted on the stationary shaft extending through slots formed in the piston, and turnably mounted slotted members in the piston opened at one end and forming guides for the vanes and provided with 70 closed ends journaled in the piston.

3. A rotary pump comprising a cylindrical casing, a rotary piston eccentrically disposed therein and radially slotted, each slot opening at one end through the piston and 75 formed with a bearing recess extending beyond the opposite end of the slot, a bearing pin journaled in the bearing recess and formed with a slot extending through one end in coincidence with the piston slot, the 80 closed end of the bearing pin journaling in the extension of the bearing recess, a vane slidably and rockably supported by the bearing pin, and a concentric shaft arranged in the casing and connected to the vane. 85

4. A rotary pump comprising a cylindrical casing, a rotary piston eccentrically disposed therein and radially slotted, each slot opening at one end through the piston and formed with a bearing recess extending beyond the opposite end of the slot, a bearing pin journaled in the bearing recess and 90 formed with a slot extending through one end in coincidence with the piston slot, the closed end of the bearing pin journaling in 95 the extension of the bearing recess, a vane slidably and rockably supported by the bearing pin, a concentric shaft arranged in the casing and connected to the vane, and means removably closing the opened ends of 100 the slots to hold the vanes therein.

5. A rotary pump comprising a cylindrical casing, a rotary piston eccentrically disposed therein and radially slotted, each slot opening at one end through the piston and 105 formed with a bearing recess extending beyond the opposite end of the slot, a bearing pin journaled in the bearing recess and formed with a slot extending through one end in coincidence with the piston slot, the closed end of the bearing pin journaling in the extension of the bearing recess, a vane slidably and rockably supported by the bearing pin, a concentric shaft arranged in the casing and connected to the base, and a ring 110 detachably secured to the piston across the opened ends of the slots for retaining the vanes operative.

In testimony whereof I have hereunto set my hand in the presence of two subscribing 115 witnesses.

JACOB JACOBSEN.
